(57) CLAIM

The ornamental design for a drive unit for running toy, as shown and described.

DESCRIPTION

FIG. 1 is a front, bottom perspective view of a drive unit for running toy showing our new design;

FIG. 2 is a rear, top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The drawings include surface shading which illustrates contour and not surface ornamentation.

The broken lines depict portions of the drive unit for running toy which form no part of the claimed design.

1 Claim, 8 Drawing Sheets
